PORTABLE VIEWING SCREEN HANDLE AND LOCK THEREFOR

Gilford D. Hudson and Frank D. Sayger, Warsaw, Ind.,
assignors to Da-Lite Screen Company, Inc., Warsaw,
Ind., a corporation of Illinois

Filed July 22, 1960, Ser. No. 44,608
1 Claim. (Cl. 287—58)

This invention relates generally to handles for carrying a portable viewing screen, and more particularly to a handle having the dual job of carrying a portable screen in its closed position, and for adjusting its position with respect to the standard for supporting the portable screen.

It is a principal object of this invention to provide a carrying handle for a portable viewing screen, said handle being characterized by ready adjustment on its supporting standard when it is desired to set up the screen.

Another object is to provide a readily adjustable handle characterized by having a locking device which is readily supported, and which cannot be separated from the handle, which is simple in construction and operation and inexpensive to manufacture.

Other objects and important features of the invention will be apparent from a study of the specification following taken with the drawing which together describe and illustrate a preferred embodiment of the invention. Other embodiments may be suggested to those having the benefit of the teachings herein and such other embodiments are intended to be reserved especially as they fall within the scope and spirit of the subjoined claim.

In the drawing:

FIGURE 1 is an isometric view of an improved handle according to the present invention; a locking device for the handle being shown in exploded position with respect thereto; and

FIG. 2 is a perspective view showing the handle of FIG. 1 in position on a standard supporting a portable viewing screen.

FIG. 3 is a perspective view of a portable picture screen of the general form to which this invention relates showing its legs in their spread position for supporting the standard erect and its screen casing or housing turned to and latched in a position parallel with the standard.

Referring now to the drawing, the improved handle according to the present invention is referred to generally by the reference numeral 10 and includes an elongated body member 11 adapted to slide upon a standard 12 and supporting a viewing screen housing or casing 30. The elongated body member 11 is preferably made in a die-cast operation, and has an upper end wall 13 thereof provided with a rectangular shaped aperture 14 providing a guide for the standard 12, which also has a rectangular shaped cross section of a dimension so as to readily slide in the aperture 14.

The elongated body member 11 includes a body element 16 extending along the standard 12 and spaced therefrom, the body element 16 including spaced sides 17 which are also spaced from the standard 12. The body element 16 and the sides 17 have an extension 18 therefrom with an aperture 19 therein in alignment with the aperture 14. The apertures 14 and 19 guide the body member 11 along the standard 12.

Handle means 21 extend from the elongated body 65 member 11 in a direction generally parallel to the body element 16 and the standard 12, the handle means 21 being spaced as shown from both the body member 16

2

and the standard 12. Sides 22 of the handle means 21 are generally co-extensive with the plane of the spaced guides 17 extending from the body element 16.

Means are provided for locking the handle 10 in position on the standard 12, and to this end one of the sides 17 has a threaded aperture 23 adapted to threadably receive a crank 24 having a handle 26, the crank 24 being turned wherein the end 24' abuts and frictionally clamps the body member 11 to the standard 12, and prevent shifting of the handle relative to the standard.

Structure is provided for limiting the rotation of the crank 24 in release movement when releasing the clamping engagement between the handle 10 and the standard 12, and to this end a pin 27 extends from one of the sides 17 and is adapted to engage with a throw 28 of the crank 24 to restrict rotative movement thereof, and prevent displacement of the crank 24 from the handle.

The body element 16 has an opening 29 therein for the reception of the usual rotatable connection (not shown) formed on the cradle 31. The cradle 31 secures the screen casing or housing 30 thereto in the usual manner.

The usual portable picture screen also is provided with an extension rod 32 slidably mounted in the standard 12, cooperative case latching means 33, 34 for releasably securing the casing parallel to the standard, and foldable legs 35 forming a tripod for the structure. Such a structure is shown in Patent No. 2,708,559, granted May 17, 1955 to Du Mais.

Although but one specific embodiment of this invention is herein shown and described, it will be understood that details of the construction shown may be altered or omitted without departing from the spirit of the invention as defined by the following claim.

We claim:

- A locking device of the class described comprising,
  - (a) a pair of telescopically-shiftable members, one of the members having a threaded opening in one side thereof extending through the one member to the exposed face of the other member, and
  - (b) a crank-handle clamping-element having a threaded hub-end of axial length greater than that of the one-member opening, and threaded into the one member opening for axial shifting toward and away from contact with the exposed face of the other member,
  - (c) and a pin fixed on the one member in position to engage the clamping element and limit the swinging of the crank handle,
  - (d) whereby the opposite swinging of the crank handle effects the axial shifting of the hub end into and out of position to respectively lock the members against or release them to permit telescopic adjustment.
